(Cl. D58—12.6)

FIG. 1

FIG. 2

FIG. 3

FIG. 4

FIG. 5

FIG. 1 is a top perspective view of a plastic box showing my new design, in open position;

FIG. 2 is a top perspective view thereof in closed condition;

FIG. 3 is a side elevational view thereof;

FIG. 4 is a bottom plan view thereof; and

FIG. 5 is a rear elevational view thereof.

The closely spaced parallel lines on the inner part of the lid and around the outer edge of the inner tray represent alternate ridges and grooves.

I claim:

The ornamental design for a plastic box, as shown and described.
